UNITED STATES PATENT OFFICE.

ANTON RAIA, OF GARFIELD, NEW JERSEY.

INTERNAL-COMBUSTION ENGINE.

1,274,329.

Specification of Letters Patent. Patented July 30, 1918.

Application filed June 25, 1917. Serial No. 176,830.

To all whom it may concern:

Be it known that I, ANTON RAIA, a citizen of the United States, residing at Garfield, in the county of Bergen and State of New Jersey, have invented certain new and useful Improvements in Internal-Combustion Engines, of which the following is a specification.

This invention relates to internal combustion engines, and it relates more particularly to an improved valve mechanism and the co-operative ports.

One of the objects of this invention is to provide, in connection with a multiple cylinder engine, a multiple valve member of improved and very effective construction.

Another object of the invention is to provide a valve member which not only allows the entrance of the combustion fluid into the cylinders, but also operates to force the combustion fluid into the cylinders.

Another object of the invention is to provide a multiple cylinder engine with counterpart valve members one of which forces the combustion fluid into the cylinders, while the other creates a suction for sucking the products of combustion from the cylinders.

Another object of the invention is to provide means whereby the valve members are allowed to be easily removed and replaced when necessary for cleaning or repairing.

Other objects and advantages may become apparent to persons who read the following detailed description and claims in connection with the accompanying drawings, in which:

Figure 1 is a horizontal sectional view through one form of embodiment of my improved cylinder casting and through one of the valve members carried thereby:

Fig. 2 is a vertical sectional view taken along the line 2—2 of Fig. 1:

Fig. 3 is a somewhat modified form of embodiment of the invention:

Fig. 4 is an enlarged vertical sectional view taken on the line 4—4 of Fig. 1: and

Fig. 5 is an enlarged fragmental vertical sectional view taken on the line 5—5 of Fig. 1.

Referring to these drawings in detail, in which similar reference characters corre-

spond to similar parts throughout the several views, the main casting or engine body 10 is of ordinary construction with the exception of the upper portion which comprises the novel construction embodying the 55 flared ports and the seats for the improved valve shafts or members 11 and 12. These valve members are of similar construction, and either of them may be considered as the intake valve member or the exhaust valve 60 member; but, for the sake of convenience in describing the device, the member 11 is considered as the intake member, and the member 12 is considered as the exhaust member.

The shafts or valve members 11 and 12 are 65 each hollow throughout the greater portion of its length, but each is closed or plugged at one end by means of a core or filler 13, and at its other end, by means of a stub shaft 14 on which is carried a gear wheel 15; 70 the stub shaft being secured within the tubular valve member by any appropriate means.

Bearings or valve seats 16 and 17 are provided for the respective valve members 11 75 and 12, into which are fitted the annular ribs 19 which are formed around the valve members 12 and 13. The ribs 19 are arranged in pairs, and between the ribs of each pair a valve-port 20 is provided for 80 the intake member, while valve-ports 21 are provided for the exhaust valve member, these valve-ports being arranged in a stepped or helical series around the respective valve members, so that each port 20 and 85 21 comes into effect at a time when the other ports of its helical series is non-effective, as will hereinafter appear more clearly.

In the preferred form of the invention—
Fig. 2—the engine embodies a main casting 90 10 and a cap 10' and between these parts are disposed ports 24 and 25 which are formed partly in each. Valve seats 16 and 17 are formed in the outer vertical walls of the engine body and extend partly into the main 95 casting or block 10 and cap 10'.

The valves 11 and 12 are retained in the respective seats 16 and 17 by caps 22 which are secured at their ends to the parts 10 and 10' by means of bolts 23. It will thus be ob- 100

served that the caps 22 close the valve seats and serve as retaining means to hold the valves in their seats and as connecting means between the cylinder block 10 and the cylinder head 10'. The caps 22 are each provided with spaced arcuate grooves 18 which receive the respective ribs 19, while the arcuate shoulder 22' of each cap 22 extends between the ribs of the contiguous pair for 10 preventing longitudinal movement of the valve member with relation to the main casting. The main casting illustrated in Figs. 1 and 2 is provided with flared or inwardly diverging intake ports 24 and exhaust ports 25 with which the valve-ports are brought into registry when the valve members are rotated. Because of the inwardly flared intake ports, the combustion fluid is allowed to expand as it enters the respective cylinders 26; and because of the inwardly flared or outwardly converging exhaust ports, the products of combustion are compressed as they are forced outward into the exhaust valve member. In other words 25 the compression of the products of combustion is made easy by the omission of any obstruction, between the cylinder and the exhaust valve member, other than the plain and smooth walls of the exhaust ports.

30 Although it is considered within the scope of this invention to rotate the valve members 11 and 12 in opposite directions, I have illustrated means comprising a pair of gear wheels 27 and a shaft 28, whereby the gears 35 15 and their respective valve members are rotated in the same direction, as is also shown by the arcuate arrows in Figs. 4 and 5. Referring to the latter figure, and to Fig. 1, it will be seen that the valve member 40 11 is provided with an annular series of blades 29, while the exhaust valve member is provided with an annular series of blades 30. Each blade 29 and 30 is inclined with relation to the radial line which passes 45 therethrough. However, the direction of inclination of the blades 29 is opposite to that of the blades 30. This opposite relation of the blades 29 and 30 is for the purpose of inducing the inward flow of the combustion fluid and inducing the outward flow of the products of combustion. To explain this feature more fully, it should be understood that 31 represents the universal intake port, and that 32 represents the universal exhaust 50 55 port. When the valve members 11 and 12 are rotated in the direction of their arcuate arrows, the blades 29 are rotated in such direction as to draw the fluid from the universal intake port into the universal intake member 11, which latter discharges such fluid through the valve openings 20 as each of these valve openings moves into registry with the valve opening 24; at the same time, the universal exhaust valve member

12 is carrying its blades 30 in such direction 65 as to gather the products of combustion from its interior and to discharge such products of combustion into the universal exhaust port 32. It will be seen, therefore, that the blades 29 coöperate with the pistons 70 75 33 for effecting the intake of the combustion fluid, while the blades 30 coöperate with the pistons 33 for effecting the exhaust of the products of combustion.

In the modified form shown in Fig. 3, the main casting 10^a differs from the casting 10, in that the cap 10^b is separable and is secured in position on the casting 10^a by means of screws or bolts 23^a. Therefore, the ports 24^a and 25^a are each approximately half 80 formed in the lower casting 10^a, and half formed in the upper casting or cap 10^b. The cap 10^b may be formed in one piece and comprise cylinder heads for the respective cylinders 26, or each cylinder head 85 may be separable from the other cylinder heads.

From the foregoing, it will be seen that I have provided a novel construction and arrangement of valves and ports which will 90 greatly improve the efficiency of internal combustion engines, and it is believed that this novel construction and arrangement will become very popular and meet with great commercial success.

95 Although I have described these embodiments of the invention in minute detail, it is to be understood that I do not limit my invention to these exact details of construction, but my invention embraces such modifications that fall within the scope of the appended claims.

What I claim as my invention is:

1. An internal combustion engine, comprising a main casing in which is formed a plurality of cylinders, a cap closing the cylinders, there being oppositely flared intake and exhaust ports between the cap and casing formed partly in each and connecting with the respective cylinders, said ports having their larger ends in communication with the cylinders and their smaller ends facing outward, hollow rotary valves closed at their ends and having a middle and side ports, the latter disposed to successively register with the outer ends of the respective ports of the cylinders, each of the valves having annular ribs at the ends of the several ports, and the middle port provided with spaced blades extending around the 110 sides of the valve and being relatively inclined.

115 2. An internal combustion engine, comprising a main casing having a plurality of cylinders therein, a cap closing the cylinders, there being ports leading outwardly from the cylinders and valve seats at the outer ends of the ports, both the ports and

valve seats being partly formed in the casting and cap, rotary valves mounted in the said valve seats, and caps closing the valve seats and holding the valves in place and
5 secured at their ends to the main casing and the cap thereof closing the cylinders.

In testimony whereof I affix my signature in presence of two witnesses.

ANTON RAI.
